UNITED STATES PATENT OFFICE.

CHARLES S. PROUDFOOT, OF WESTMONT BOROUGH, AND DAVID L. EYNON, OF ST. DAVIDS, RADNOR TOWNSHIP, DELAWARE COUNTY, PENNSYLVANIA.

CAR-TRUCK SIDE FRAME.

Application filed February 24, 1923. Serial No. 620,893.

To all whom it may concern:

Be it known that we, CHARLES S. PROUDFOOT, a resident of the borough of Westmont, in the county of Cambria and State 5 of Pennsylvania, and DAVID L. EYNON, a resident of St. Davids, Radnor Township, in the county of Delaware and State of Pennsylvania, both citizens of the United States, have invented certain new and use- 10 ful Improvements in Car-Truck Side Frames; and we do hereby declare the following to be a full, clear, and exact description of the invention, such as will enable others skilled in the art to which it ap- 15 pertains to make and use the same.

Our invention relates generally to an integrally formed side frame which is adapted for use under various classes of cars, and particularly freight cars of large capacities, 20 and our frame has all of its principal members formed from one plate of metal, such as steel or iron, which is first cut or sheared to the outlines desired to produce the different members, flanges are formed on the 25 said plate of different lengths on the various members extending substantially at right angles to the spaced side portions of the frame and joined to the sides by slightly rounded portions, and then the plate is 30 bent about its median line and the two side portions brought into substantial parallelism, spaced apart a predetermined distance, with the inturned flanges opposite each other.

One of the particular features of our invention resides in connecting the inturned flanges of the various members together by means of integral tongue and groove connections, and in order to accomplish this 40 we provide other integral flanges extending outwardly from the inturned flanges, one on one side of a member and another on the other side thereof. One of these outstanding flanges is provided with notches 45 therein of a depth substantially equal to the thickness of the plate forming the frame, and the other outstanding flange on the companion portion of the member is provided with integrally formed bent por- 50 tions having grooves therein, in which the tongue of the other portion is tightly seated, this tongue and groove connection thus securing the two parts of the member very

firmly together, or tongues and grooves may be on each flange. 55

When complete, the outstanding flange with the tongue and that with the groove portion have their outer edges in substantial alignment, thereby presenting a pleasing appearance, this being due to notches 60 cut in the tongue portion, thus keeping the outside edges in line.

Our truck frame is of substantial over-all width corresponding to standard dimensions for such parts, and for example, the 65 width may be six inches, more or less, as desired, and the members are hollow, thus producing a strong and at the same time an economical structure.

The members are formed integral, as before stated, and comprise a top arch bar, inclined tension members with their upper ends joined with the top arch bar, these two parts being merged together, thereby providing deep end portions of box section, 70 well adapted to withstand the bending and other stresses of use. Our frame also comprises upright column guides integrally joining the top arch bar with the bottom arch bar, and we also prefer to form the 75 pedestal tie bars integral with the lower portion of the frame, their inner portions being generally of channel section, while parts of their end portions are of double thickness, flat and composed of two layers 80 of plate, one of which is part of one side of the frame, while the other layers are part of the other side. Journal box bolt 85 holes are provided in the end extensions and in the pedestal tie bars to secure the journal boxes to the frame. A bolster opening is also provided in the center of the frame and at each side of its upper portion a plate or pad is secured thereto to form the 90 bolster guides, and we also provide other 95 openings in the frame between the bolster openings and the ends of the frame to lighten the structure and to allow access to the brake shoes and other inner parts of the truck. 100

We prefer to make tongue and groove connections only on certain of the members where necessary to give strength to the structure and hold the parts together, while some members or portions of members may 105 have inturned flanges which are opposite

each other with their edges spaced apart, or in other cases the inturned flanges may be longer and abut each other and may be secured together by welding or otherwise to produce a closed section.

Having thus given a general description of our invention, we will now, in order to make the matter more clear, refer to the annexed sheet of drawings, which forms part of this specification, and in which like characters refer to like parts:—

Figure 1 is a side elevation of our car truck side frame; Figure 2 is a bottom plan view, looking upwardly; Figure 3 is an end elevation, Figure 4 is a vertical cross sectional elevation on the line IV—IV of Figure 1 through the central portions of the top and bottom arch bars; Figure 5 is a cross section through the central portion of the inclined tension member on the line V—V of Figure 1; Figure 6 is a cross section of a part of the pedestal tie bar extension taken through the tongue and groove connection on the line VI—VI of Figure 1; Figure 7 is a horizontal cross section through the upper portion of a column guide showing the guide plate secured thereto, taken on the line VII—VII of Figure 1; Figure 8 is a cross section taken through the intermediate portion of the end of one of the pedestal tie bars central with the journal, on the line VIII—VIII of Figure 1; Figure 9 is a horizontal cross sectional plan through the lower part of the bolster opening and the adjacent column guides taken on the line IX—IX of Figure 1, showing the spring plank in dotted lines, and Figure 10 is a cross section taken near the end of one of the pedestal tie bars in the plane of the axis of the outer journal box bolt, taken on the line X—X of Figure 1.

Referring now to the characters of reference on the drawings:—1 is the central portion of the top arch bar generally; 2 is the central portion of the bottom arch bar; 3 are the end extensions adapted to rest on the journal boxes; 4 are inclined or diagonal tension members which join the bottom and the top arch bars and merge into the latter to form the end extensions 3; 5 are the column guides which extend in an upright direction and join the top and bottom arch bars, etc.; 6 are the pedestal tie bars in general, all of these parts being formed integral from one plate. Openings 7 are provided between the bolster opening and the ends, and these are shown of circular form, but they may be of any other shape desired. The top of the truck frame in general is the upper plate portion 8, with the two side portions 9 integrally formed and projecting downwardly from the same, forming the sides of the various members. The top arch bar has inwardly projecting flanges 10, the edges of which are spaced apart as illus-

trated; 11 are the bottom inturned flanges of the end extensions 3, the edges of which abut each other, and if desired may be secured together by welding or otherwise. The bottom arch bar is provided with upper inturned flanges 12, the edges of which are spaced apart as shown, and its lower part has inturned flanges 13 which abut each other, and these are provided with other flanges 14 formed integral therewith and projecting outwardly or outstanding therefrom, and these flanges 14 have notches therein of a depth substantially equal to the thickness of the plate, and parts of them are also provided with extending portions 16. The material of the outstanding flanges 14 at the base of the notches forms tongues 15 and each of the extension portions 16 of the companion flange, which are of a width substantially equal to the length of the notches in the other flange, is bent as illustrated to form a groove in which the tongue 15 of the companion flange 14 is seated and locked. Between these tongue and groove portions the outwardly extending flanges 14 are continued and their edges are in alignment with the outer parts of the portions 16 containing the grooves, so that the outer line of these portions is unbroken, continuous and pleasing. The inclined tension member 4 has inwardly projecting flanges 17 adjacent the hole 7, which are spaced apart and its lower side has outwardly projecting flanges 18. These outstanding flanges 18 also have tongues 15 and bent portions 16 each formed with a groove in which the tongue is seated as previously described. The column guides are provided with pairs of inturned flanges 19, parts of which are abutting and the other parts have their edges spaced apart, and to the upper portions of the column guides the bolster guide plates 20 are secured by welding or otherwise. The inner portion of the pedestal tie bar is provided with upturned flanges 21 and its lower portions are provided with tongue and groove members 15 and 16, respectively, similar to those previously described. The outer portions or extensions of the pedestal tie bars are formed of two parts, one integral with one side of the frame and the other with the other side, and these have flat upper surfaces 22, which are seated against the bottoms of the journal boxes, and these extensions are joined between the journal box bolts by means of tongue and groove portions 15 and 16, respectively, similar to those previously described. The extreme end portions of the pedestal tie bars are 23 and 24, as particularly illustrated in Figures 1, 2 and 10. The inturned flanges 19 at the lower ends of the column guides have parts of their edges contiguous and other parts spaced apart as particularly illustrated in Figures 4 and 9; and 25 are reinforcing plates shown of chan-

nel form with their webs cut in trapezoidal shape and mounted within the end extensions of the frame in order to reinforce this portion, and they may be welded or otherwise secured thereto. The lower portions of these reinforcing plates have upturned lips as shown to serve as nut locks for the journal box bolts.

As indicated in Figure 1, the wheels, journal boxes, journal box bolts, etc., are shown in dotted lines, and as viewed in Figure 9 a portion of the spring plank 26 is also indicated in dotted lines.

Our frame is preferably made in the following manner: A plate of metal such as iron or steel, about one-half inch or thereabouts in thickness and substantially rectangular, is placed on a powerful shearing press and cut to shape thereon in one or more operations as desired, this cutting or punching being preferably done cold in order to maintain the various dimensions. After this is done the plate is preferably heated and placed in a powerful flanging press provided with suitable dies, and the various flanges thereof are pressed integrally therefrom, and some of these extend at substantially right angles to the body of the plate and are joined thereto by rounded corners with various radii, while on some of these flanges other outstanding flanges are also formed, which are provided with tongue portions 15 and others having portions 16, in which are to be formed the grooves to receive the tongues. The outer edge of the portion forming the groove may at first extend substantially parallel to the inturned flanges, and after this is done the plate is placed in another press and bent about its median line and the two sides made to approach each other, so that like parts are substantially opposite, and the side portions are then closed together with some parts in contact. This causes the tongue portions 15 to be seated in the places provided for them, and after this is done the edges of the flanges 16, which form the grooves, are bent around the tongues and clamp the same firmly.

It will be noted that the portions forming the tongues are of less depth than the body of the flanges on which they are formed by an amount substantially equal to the thickness of the plate, so that when the tongue is in the groove the outer edges of the combined outstanding flanges are substantially in alignment and continuous, thus making a uniform structure of neat appearance.

It should also be noted that we may form some of the tongue portions on one side of the frame and some of the grooved parts on the same side, and similarly for the other side, although if desired we may have all the tongue portions on one side and all of the grooved portions

on the other side, as will be readily understood.

The reinforcing plates 25 are inserted and secured in place and the bolster guide plates 20 are also placed in position and secured to the upper parts of the column guides by welding or otherwise.

It will thus be seen that by means of our invention we provide a very simple and effective construction for securing certain parts together by means of their outwardly extending flanges and the tongue and groove connections thereof, while the other part of the grooved portion is in line with the outer edge of the outstanding flange of the tongue portion between these connections, so as to provide a compact structure and a continuous or unbroken outline.

Although we have shown and described our invention in considerable detail, we do not wish to be limited to the exact and specific details thereof as shown and described, but may use such modifications in, substitutions for, or equivalents thereof as are embraced within the scope of our invention or as pointed out in the claims.

Having thus described our invention, what we claim and desire to secure by Letters Patent is:—

1. An integral side frame for a car truck, composed of various members, some of which are provided with outstanding flanges secured together by integral tongue and groove connections, the tongue portions of said flanges being of less length than the other portions of the said flange, whereby the outer surfaces of said connections are in alignment.
2. An integral side frame composed of one plate, certain members of which are secured together by tongue and groove connections arranged at intervals with their outer edges in substantial alignment.
3. A truck frame composed of one metal plate, having a top portion, two side portions extending therefrom and spaced apart, some of the members having integral inwardly extending flanges provided with outstanding tongue and groove connections, the tongue portion being formed in a notch in the outstanding flange in such a way that the outer edges of said connections are in substantial alignment.
4. A truck frame composed of one metal plate, having a top portion, side portions extending therefrom and spaced apart, parts of said side portions having inwardly extending flanges provided with outwardly extending tongue and groove portions interlocking with each other, with their outer edges in one continuous line, whereby the parts are secured together.
5. A truck frame composed of one metal plate, including a top portion, a bottom portion, side portions composed of members

connecting the same, said side portions being spaced apart and some of them being provided with inturned flanges, some of said flanges having a plurality of grooved portions and others a plurality of tongue portions locked therein, with their outer edges in one continuous line, whereby the parts are firmly secured together.

6. An integral frame for car trucks, composed of a single plate of metal forming the various members thereof, having a top member, side members extending from the upper member in substantial parallelism and spaced apart, a bottom member, inwardly extending flanges on certain of said members co-operating with each other, one of the same having a plurality of grooved portions and the other a plurality of tongues, adapted to interlock and thereby secure the parts together, their outer edges being in one continuous line.

7. A side frame for car trucks of the integral arch bar type, comprising a single plate of metal bent about its intermediate portion, forming a top arch bar, a bottom arch bar, inclined tension members, column guides and pedestal tie bars, certain of the members having inturned flanges adapted to contact with each other, some of said flanges being provided with a plurality of integral tongue portions, and its companion having a plurality of internally grooved portions adapted to interlock, with their outer edges in one continuous line, whereby the parts are firmly secured together.

8. A side frame for car trucks, comprising a single plate of metal bent about its intermediate portion, forming a top member, a bottom member, and side members, the sides of which are spaced apart, some of them having inturned flanges, portions of said flanges being provided with integral tongues, and integral grooves in the adjacent portions, adapted to interlock and secure the parts together, with their outer edges forming one continuous line.

9. A truck frame composed of one metal plate, having a top portion, a bottom portion, and two side portions extending therefrom and spaced apart, some of the members, including said side portions, being

provided with outstanding tongues and others with outstanding grooved portions, all formed integral therewith, extending throughout parts of their entire lengths, with their edges in one continuous line, whereby the members are firmly secured together without welding or riveting.

10. A side frame for car trucks, composed of a single plate, cut in the shape desired to form the various members, including a top arch bar, a bottom arch bar, inclined tension members, column guides, and pedestal tie bars, the side portions of which connecting the arch bars are spaced apart and provided with inturned flanges, some of which are opposite and spaced apart, and some with abutting flanges provided with interlocking tongue and groove portions, with their outer edges in one continuous line.

11. An integral side frame of the arch bar type formed of a single plate bent on its median line with side portions spaced apart and extending downwardly therefrom, shaped to form the various members, including end portions adapted to rest on the journal boxes, a top arch bar, inclined tension members merging into the ends of said top arch bar and forming end extensions adapted to rest on the journal boxes, a bottom arch bar with integrally formed pedestal tie bars forming end continuations thereof, column guides extending in an upright direction and joining the top and bottom arch bars, openings between the column guides and the end members, a central bolster opening, integral inturned flanges formed on various of the members, some of which are abutting and some of which are opposite and spaced apart, and connections between some of the flanges of the various members comprising integrally formed tongues on one of the inturned flanges and bent portions forming grooves on the companion flange, with their outer edges in one continuous line, these being nested to form a lock joint, whereby the parts are firmly secured together.

In witness whereof we hereunto affix our signatures.

CHARLES S. PROUDFOOT.
DAVID L. EYNON.
